UNITED STATES PATENT OFFICE.

JOZSEF NAGY, OF CLEVELAND, OHIO.

CAR COUPLING AND BUMPER.

No. 918,580.

Specification of Letters Patent.

Patented April 20, 1909.

Application filed February 29, 1908. Serial No. 418,508.

To all whom it may concern:

Be it known that I, JOZSEF NAGY, subject of Franz Joseph, Emperor of Austria-Hungary, residing at Cleveland, in the county 5 of Cuyahoga and State of Ohio, have invented certain new and useful Improvements in Car Couplers and Bumpers, of which the following is a specification.

This invention is a car coupler of the type 10 in which one car has a socket with hooks therein and the other has a rod or bar with a head which is engaged by the hooks when it is forced into the socket as the cars come together.

15 The object of the invention is to form an improved coupler of the kind stated, having also improved means for releasing the coupler when desired.

20 The invention is illustrated in the accompanying drawings, in which—

Figure 1 is a side elevation of the coupling. Fig. 2 is a top plan view with the top plate of the parts removed. Fig. 3 is a top plan view of one of the coupler heads.

25 One draw head or casing is formed of upper and lower parts 1 and 2 which when fitted together form a recessed head which contains the spring hooks referred to. The other draw head is formed of upper and 30 lower casings 3 and 4 which inclose the coupling bar. These parts 1 and 2 and 3 and 4 are secured together by bolts or other suitable means. The coupling bar 5 projects from the casing formed by the parts 35 3 and 4 and has at the outer end a head 5^a with square shoulders on opposite sides. At its inner end it has a cross pin 6 which moves in a slot 8 formed in each side of the casing. A coiled spring 7 bears against 40 the cross pin at one end and against a partition 9 at the other end and acts to cushion the shock on the coupling bar. The spring is contained in a recess formed in the back part of the casing. The hooks 22 are 45 mounted in the other casing upon a central pivot 23, said hooks having the form of levers with arms extending to the pivot referred to. They are arranged to engage over the head 5^a when said head is forced 50 therebetween. A spring 20, between the rear ends of the hooks, serves to close the front end of the hooks and cause them to engage over the head of the coupling bar.

55 Located between the hooks is a block 24 with a forwardly presented concave surface, and said block has a rearwardly extending

stem 26 which telescopes into a tube 27 the rear end of which has a hole through which the pin 23 extends. A spring 25, coiled around the stem and tube tends to advance 60 the block and cushions the impact of the head 5^a against the same. A pin 28 extending through slots in the stem and the tube prevents accidental separation of the parts. 65

To open the jaws 22 a vertical shaft 12 is 65 provided, located between the rear ends of the jaws and connected thereto by chains 19. This shaft extends through the top of the casing and has at its upper end a beveled gear 17 which meshes with a beveled gear 16 on a cross shaft 14 which is provided at its outer end with a crank handle 15 which may be located at the side of the car so as to be accessible to a train man without having to enter between the cars. The upper and 70 lower plates of the casing are strengthened, where the pin 23 is held, by fillets 11 around the holes through which said pin extends. 75

When the crank 15 is turned the gearing causes the chains to wind up on the shaft 80 and draws the rear ends of the hooks together, thereby opening the same at the front and allowing the coupling bar 5 to be pulled out or disconnected. When the crank 85 is released the spring 20 throws the hooks together in position to reengage the head of the coupling bar when the same is again forced therebetween. An advantage arises from the fact that the movable parts of the coupling are inclosed or incased and consequently are not apt to be rendered inoperative by deposits of snow or sleet thereon. It is also unnecessary for the train man or attendant to hold the coupling bar in his 90 hands to enter the same between the jaws or 95 hooks.

I claim:

A car coupling member comprising a hollow drawhead having opposite spring-pressed hooks therein, a pin on which the 100 hooks are pivoted, and a spring-supported block between the hooks and connected at its rear end to the pin and adapted to receive the impact of a head inserted between the hooks. 105

In testimony whereof I affix my signature, in presence of two witnesses.

JOZSEF NAGY.
